(57) **CLAIM**

The ornamental design for a knife, as shown and described.

DESCRIPTION

FIG. 1 is a top isometric view of a knife showing our new design;

FIG. 2 is a bottom isometric view thereof;

FIG. 3 is a top view thereof;

FIG. 4 is a right side view thereof;

FIG. 5 is a handle end view thereof;

FIG. 6 is a bottom view thereof;

FIG. 7 is a blade end view thereof; and,

FIG. 8 is a left side view thereof.

The broken line showing on the blade is for illustrative purposes only and forms no part of the claimed design.
